UNITED STATES PATENT OFFICE.

JOHN E. CASTER, OF CINCINNATI, OHIO, ASSIGNOR TO CINCINNATI GRINDERS INCORPORATED, OF CINCINNATI, OHIO, A CORPORATION OF OHIO.

GRINDING MACHINERY.

Application filed July 27, 1927. Serial No. 208,869.

This invention relates to improvements in grinding machinery and has particular reference to a machine adapted for the grinding of balls or similar contoured articles.

5 One of the purposes of the present invention is the provision of a mechanism applicable to commercial centerless grinders which will make it possible to rapidly and accurately produce balls such as employed 10 in ball bearings upon said machine.

A further object of the present invention is the provision of an improved control mechanism for governing the position and advance of a plurality of work pieces into 15 and through the grinding throat.

Another object of the invention is the provision of a machine for the production of spherical articles in accordance with the centerless principle of grinding which shall 20 automatically control the supplying of the articles to be ground and the progress of the articles during grinding and which will prevent accidental displacement of pieces being operated upon during the time that new 25 or additional pieces are being supplied to the machine.

An additional object of the invention is the provision of a positively controlled ball grinder which shall be substantially continuous in operation and therefore within maximum production.

Other objects and advantages of the present invention should be readily apparent by reference to the following specification taken 35 in conjunction with the accompanying drawings forming a part thereof, and it will be understood that I may make any modifications in the specific structural details hereinafter disclosed within the scope of the appended claims without departing from or 40 exceeding the spirit of the invention.

Figure 1 is a front elevation of a machine embodying the present improvements.

Figure 2 is a vertical sectional view on 45 the line 2—2 of Figure 1.

Figure 3 is a detail sectional view on line 3—3 of said figure.

Figure 4 is a section as on line 4—4 of Figure 1 showing the work piece engaging 50 and advancing structures.

Figure 5 is a vertical section on line 5—5 of Figure 4.

Figure 6 is a horizontal or transverse section as on line 6—6 of Figure 5.

55 Figure 7 is an enlarged detailed view of the

work piece carrier advancing mechanism on the line 7—7 of Fig. 4.

Figure 8 is a fragmentary view illustrating the feed control.

Figure 9 is a vertical section on line 9—9 of Figure 8.

Figure 10 is a view of a modified form of magazine controlling device, and

Figure 11 is a section on line 11—11 of Figure 10.

Figure 12 is a fragmentary section illustrating the cam operated infeed control mechanism.

Figure 13 is a fragmentary view of the work rest and regulating wheel indicating 70 the relationship of said parts.

As distinguished from ball grinding machines of the prior art in which a series of balls have been placed in an uncontrolled manner as in a continuous 75 groove for example between grinding members, the present invention contemplates the grinding of individual balls in individual distinct grooves while retaining the ball against advancing movement in its 80 groove. The invention further contemplates in place of utilizing a single continuous groove in which the work piece rolls, a plurality of grooves to which the work pieces are successively transferred, so that one 85 groove may perform the initial roughing out cut and subsequent grooves will work the ball down to its proper final size.

One embodiment of a machine for accomplishing these results is illustrated in the drawings in which the numeral 15 designates the bed of a conventional centerless grinding machine bearing the grinding wheel 16 and the slide 17 for the regulating wheel control unit 18 which supports the regulating wheel 19 for in and out movement. This in and out movement may be manually effected by rotation of adjusting screw 20 or automatically accomplished through suitable mechanism contained in the shifter box 21 driven from motor 22.

One form of this mechanism for imparting an automatic in and out movement to the regulating wheel is illustrated in copending application 102,762.

This mechanism includes a rotatable cam 23 operating a toggle 24 which imparts an in and out or reciprocating movement to the regulating wheel slide 17. This member is further formed with a face lug or 110

cam portion 25 actuating plunger 26 which is provided with a rack 27 meshing with pinion 28 on rock shaft 29. This shaft is journalled in arm 30 carried by the intermediate slide 31. The shaft bears an arm 36 having a plurality of apertures 35 selectively engageable by the pivot pin 37 for coupling thereto, one end of link 32. The opposite end of this link is selectively engageable with apertures 38 of rock arm 33 carried by the feed mechanism housing 34. It will be understood that on account of the cam 23 controlling both the automatic in and out movement of the regulating wheel and also the oscillation of rock shaft 29 that these operations take place in timed relation one to the other, the timing being such that link 32 is raised for actuation of the feed mechanism when the regulating wheel 20 has been separated the maximum amount as respects the grinding wheel.

The general construction of the ball feeding mechanism and the relationship of the balls to the two wheels previously referred to will be best understood by reference to Figures 4 and 6. From these it will be noted that the grinding wheel 16 is formed with a multiplicity of relatively shallow grooves 39 which are shown as double in number to the number of work pieces 40 to be operated upon. Similarly, the regulating wheel 19 has a corresponding number of grooves 41 disposed at their point of contact with the work in opposition to the grooves of the grinding wheel. Attention however, is invited to the fact that the regulating wheel is preferably disposed at an angle to the plane of the grinding wheel so that it will exert a slight diagonal thrust or twisting action on the work pieces tending to present all portions thereof equally to the action of the grinding wheel. It is to be understood that in this form of machine as is customary in the operation of centerless grinding the grinding wheel is rotated in a clockwise direction as viewed in Figure 1 and at a proper grinding speed as for example five thousand feet peripheral speed per minute. The regulating wheel also operates in a clockwise direction with the result that its work engaging surface is moved upward while the grinding wheel surface moves downward with respect to the work piece. Disposed intermediate the wheels on the slide 55 is the work supporting bracket 42 having adjustably mounted thereon the work rest blade 43 vertically adjustable as by the screw actuated wedge member 44 cooperating with the pins 45 on the blade. The blade is formed with an angled upper surface 46 causing the work to be urged by gravity in the direction of the regulating wheel.

Additionally, carried by the bracket 42 is the feed mechanism housing 34 in which

is mounted the pair of axles 47 on which rotate the sprockets 48 of endless chain 49. This chain carries a multiplicity of work feeding blades or combs 50 each provided in the structure shown with three notches 70 51 providing the blocks or teeth 52 intended to project intermediate the work pieces 40 as clearly illustrated in Figures 4 and 6. The blades ride between the guide ribs 53—54 which steady the blades in their passage 75 around the housing.

By reference to Figure 4 it will be noted that the blades are so secured to the endless chain as to satisfactorily move around in the proper path at the ends, but form a 80 substantially continuous solid member while progressing into, through and beyond the grinding throat. To progress the several blades in an intermittent or step by step manner through the grinding throat, they 85 are each provided with a rack section 55 which in their lower position provides a continuous rack as indicated in Figure 7. Disposed on the housing 34 adjacent the grinding throat is a guide portion 56 having movably mounted therewithin the slide block 57 bearing a pawl 58 urged into engagement with the rack section 55 by spring 59. This block has a recess at 60 to receive the upper end of rock arm 61 secured to shaft 63 90 which bears the rock arm 33. Consequently, as rock shaft 29 is actuated the motion is transmitted by link 32 to arm 33 and thence through shaft 63 to arm 61, causing a back and forth movement of slide block 57 and its 95 associated pawl. In its retracting movement the pawl slides idly over the composite rack, the blades being held against reverse movement as by locking pawl 64 while on return or inward movement the slide block 100 pawl will carry the rack with it advancing the blades but a desired or predetermined amount. This advance may be graduated as a step by step proposition moving the balls from one groove 39 to the next groove 105 in case it is desired to perform a slight amount of grinding on each ball in each groove. On the other hand, a longer stroke or movement may be imparted in which the individual balls engage only every third 110 groove, skipping two in their advance.

In the event that the balls are to be engaged in each groove or in every other groove a continuous gravity feed mechanism may be employed for supplying work pieces 115 such as shown in Figures 10 and 11 for example. This comprises primarily a feed tube 65 having its lower end terminating in the discharge aperture 66 and having in addition a lateral notch 67 normally closed 120 by the spring pressed finger 68 having a bevelled or inclined surface 69. The individual balls roll forwardly through aperture 66 and will rest against the adjacent tooth 125 52 until it progresses in its inward move- 130

ment sufficiently to align one of the notches 51 with the ball. If the rough blank be of proper size for introduction within the machine it will then drop through the notch 5 into the guide groove 70 and be progressed along this groove to operative position on top of the work rest blade 43. In the event, however, that an unduly large work piece passes through tube 65 its size will prevent 10 its dropping entirely into notch 51 with the result that it will become slightly wedged and laterally shifted but be disposed out of operative position. The action in this instance is indicated in Figure 11, in that the 15 ball will ride against the bevelled face 69 of finger 68 pressing the finger rearwardly so that the ball may slip past. The ball will then be aligned with discharge passage 71 and in being retained by groove 70 will 20 roll outward. This action is extenuated by the engagement with the work piece of ejector point 72 which serves to pick off the oversize piece from engagement with the feed blade.

25 In the event that it is desired to advance the balls more than one groove at a time an intermittent feed mechanism such as shown in Figures 8 and 9 may be employed. There are here shown three guide ribs 73 30 extending downward into the feed block 74 in combination with a detent 75 preventing discharge of the balls, the detent being retained in locked position as by spring pressed plunger 76. To release the detent 35 and allow balls to feed into the notches 51, use is made of the mechanism particularly illustrated in Figure 8. The rock arm 33 bears at one end the rotatable notched disk 75' having a plurality of notches 76' and being additionally provided with the ratchet 77. In the upward movement of the inner end of arm 33 corresponding to the retracting movement of slide 57, ratchet 77 will be brought 40 into engagement with the adjustable pawl 45 78 carried by the guide portion 56 of the housing. This engagement will impart a partial rotation to the ratchet and its associated notched disk. Ordinarily the rotation is such that on rocking of the arm the disk 50 will be turned to bring a notch 76' into alignment with plunger 79 as shown in Figure 8. Consequently, reverse rocking of the arm will bring the disk down toward the plunger but on account of the interfitting 55 relation of notch and plunger the plunger will not be disturbed thereby. On the next rocking movement a further rotation of the disk will bring one of the teeth 80 into alignment with the plunger. Consequently reverse rocking of the arm will cause tooth 80 60 to engage and depress plunger 79, thus raising detent 75 and allowing a ball from each of the feed tubes 73 to pass into a corresponding aligned notch of the immediately adjacent blade member.

In the operation of the machine the grinding wheel is driven at a high or grinding rate of speed downwardly or toward the work rest blade while the regulating wheel moves at a slow rate of speed and with its operative surface adjacent the work rest blade moving upwardly. By action of the control cam 23 the regulating wheel is retracted from the grinding wheel to provide a space sufficient for transverse movement of the work pieces. While the parts are in this retracted position the cam lug 25 actuates rock arm 29 and through several connections serve to shift slide block 57 and pawl 58 outwardly until roller 81 moves off the lug. At this instant spring 82 expands and reversely shifts slide block 57 and pawl 58 imparting a forward feeding movement to the work guiding blades. This movement serves to align the work pieces in 85 notches 51 with the grooves in the grinding and regulating wheels, after which the cam 23 shifts the regulating wheel unit inwardly contracting the throat between grinding and regulating wheels and pressing the work 90 piece into engagement with the grinding wheel. This movement is continued until the predetermined amount of grinding has been completed. The continuous movement of the cam then again retracts the regulating wheel slide and opens up the grinding 95 throat. The cycle of operations is then repeated, new work pieces being fed from the supply tube 65 or 73 into position within the grinding throat and advanced to new 100 grooves.

The advantage of this type of action is that the grinding wheel being contoured reproduces on the work the desired shape, while the substantially contoured surface of the regulating wheel insures a proper gripping action of this wheel against the work to control its rotation, to prevent spinning and to present all portions of the work surface equally to the grinding wheel. Stepping the balls along from one groove to the other, the rough grinding action is performed in the first or second groove and the subsequent grooves each remove less and less material, so that by the time the work piece has 110 progressed through the machine the final grooves have very little grinding to do and therefore insure accurate production of work pieces to prescribed size and with proper finish.

1. I claim:

1. A machine of the character described, including opposed grinding and regulating wheels and an intermediate work rest, said wheels having contoured work-engaging portions disposed in opposition one to the other, advanceable means for shifting the work along the throat between said wheels, and means for intermittently imparting an advancing movement thereto.

2. A machine of the character described, including opposed grinding and regulating wheels and an intermediate work rest, said wheels having contoured work engaging portions disposed in opposition one to the other, advanceable means for shifting the work along the throat between said wheels, means for intermittently imparting an advancing movement thereto, and means for automatically increasing the width of the grinding throat prior to actuation of the work advancing means.
3. A machine of the character described, including opposed grinding and regulating wheels forming a work receiving throat, a work rest disposed within the throat, means for advancing work along the rest within the throat, intermittent actuating mechanism for said means, and detent mechanism preventing reverse movement of said means.
4. In a machine for the production of contoured work pieces, the combination with opposed grinding and regulating wheels forming a work receiving throat, of a work supporting member disposed within said throat, and means for advancing work through the throat along said work support, said means including a work engaging device, means for imparting a step by step advancing movement to said device, and means preventing reverse movement of the device.
5. The combination with a centerless grinder, including opposed grinding and regulating wheels and an intermediate work rest, of a work feeding mechanism therefor, including an endless carrier having a work engaging portion disposed in the throat between the grinding and regulating wheels in opposition to the work rest, and means for imparting an advancing movement to said carrier.
6. The combination with a centerless grinder, including opposed grinding and regulating wheels and an intermediate work rest, of a work feeding mechanism therefor, including an endless carrier having a work engaging portion movable adjacent the work rest, and means for imparting an intermittent advancing movement to said carrier.
7. The combination with a centerless grinder, including opposed grinding and regulating wheels and an intermediate work rest, of a work feeding mechanism therefor, including an endless carrier having a work engaging portion movable adjacent the work rest, means for imparting an intermittent advancing movement to said carrier, and automatic means operable in timed relation to the carrier for increasing the space between grinding and regulating wheels prior to movement of the carrier and for decreasing the space subsequent to said movement.
8. The combination with a centerless grinder, including opposed grinding and regulating wheels and an intermediate work
- rest, at least one of said wheels having a contoured surface formed thereon, of means for intermittently varying the separation of said wheels, an endless carrier having its path extending between the wheels, and means for intermittently progressively advancing the carrier during separation of said wheels.
9. The combination with a centerless grinder, including opposed grinding and regulating wheels and an intermediate work rest, at least one of said wheels having a contoured surface formed thereon, of means for intermittently varying the separation of said wheels, an endless carrier having its path extending between the wheels, means for intermittently progressively advancing the carrier during separation of said wheels, and additional means for preventing reverse movement of the carrier.
10. A machine for grinding non-cylindrical articles, including a grinding wheel having a plurality of contoured grooves formed in the surface thereof complementary to the shape to be produced on a finished work piece, a regulating member opposing said grinding member for controlling the rotation of work in engagement therewith, means for intermittently varying the separation between the grinding and regulating members, a work blade movably supported between said members and having a work engaging recess, and means for progressively advancing the blade to successively align its recess with different contoured grooves in the grinding wheel, whereby a work piece in the recess will be successively presented to said grooves.
11. In a machine of the character described, the combination with an opposed grinding and regulating wheel, of a work carrier adjustable between the wheels, means for imparting an intermittent advancing movement to the carrier, means for supplying work pieces to the carrier, and a control device coupled with the carrier advancing means for intermittently supplying work pieces to the carrier as respects shifting movements thereof.
12. A machine of the character described, including opposed grinding and regulating wheels and an intermediate work support, means for intermittently advancing work along the support, including a work carrier, a feed rack thereon, a feed slide carrying a rack engaging pawl, means for positively retracting the slide as respects the rack and means for resiliently returning the slide to actuate the rack.
13. A machine of the character described, including opposed grinding and regulating wheels and an intermediate work support, means for intermittently advancing work along the support, including a work carrier, a feed rack thereon, a feed slide carrying a rack engaging pawl, means for positively

retracting the slide as respects the rack, means for resiliently returning the slide to actuate the rack, and detent means engaging the rack to prevent reverse movement thereof.

14. A machine of the character described, including opposed grinding and regulating wheels, an intermediate work support, the grinding wheel having a plurality of contoured work engaging grooves, an endless carrier having a plurality of work engaging members successively presentable between the wheels to position work pieces therebetween, and a feed mechanism successively engageable with individual work engaging members for intermittently advancing said series of members to present work engaged thereby to successive grinding wheel grooves.

15. In a machine of the character described, the combination with an advanceable work carrier, of means for intermittently advancing the work carrier, means for controlling the supply of work to the carrier, including a hopper mechanism, a 25 detent regulating discharge from the hopper, a rock arm shiftable in synchronism with the carrier, a work releasing plunger, and means on the arm adapted to engage the plunger and release the detent.

16. In a machine of the character described, the combination with an advanceable work carrier, of means for intermittently advancing the work carrier, means for controlling the supply of work to the carrier, including a hopper mechanism, a 35 detent regulating discharge from the hopper, a rock arm shiftable in synchronism with the carrier, a work releasing plunger, and intermittently operable means on the arm adapted to engage the plunger and release the detent.

17. A machine for production of contoured

work pieces, including a grinding wheel having a plurality of contoured grooves formed in the operative face thereof, a regulating wheel disposed in opposition to the grinding wheel and a work controlling mechanism comprising a housing located in a plane intermediate the wheels, an endless carrier within the housing having work engaging members projectable into the space between the wheels, and control mechanism for the machine, including a cam member, connections between the cam member and one of the wheels for intermittently varying the separation between the wheels, a rock shaft, 50 connections between the cam member and the rock shaft for intermittently rocking the shaft in timed relation to the relative shifting of the wheels, an arm coupled with the rock shaft for actuation thereby, carrier 55 shifting means coupled with the arm for synchronous operation therewith, and additional feed control mechanism carried by the arm and operable upon rocking movement thereof.

18. A machine of the character described, including opposed grinding and regulating wheels and an intermediate work rest, the grinding wheel having a plurality of contoured grooves formed in the face thereof, 70 and work controlling means movable above and in opposition to the work rest, said means having work receiving recesses, means for intermittently progressively shifting the work controlling means to successively align 75 the recesses therein with grooves in the grinding wheel surface, and means for automatically varying the separation of the wheels to permit of passage of work pieces from groove to groove of the grinding wheel. 80

In testimony whereof I affix my signature.
JOHN E. CASTER.
